UNITED STATES PATENT OFFICE.

JOHN N. FARIS, OF PORTLAND, OREGON.

FOLDING-RACK ATTACHMENT FOR IRONING BOARDS.

Application filed December 12, 1921. Serial No. 521,722.

To all whom it may concern:

Be it known that I, JOHN N. FARIS, a citizen of the United States, residing at Portland, in the county of Multnomah and State of Oregon, have invented certain new and useful Improvements in Folding-Rack Attachments for Ironing Boards; and I do declare the following to be a full, clear, and exact description of the invention, such as 10 will enable others skilled in the art to which it appertains to make and use the same.

My invention relates to improvements in clothes racks and more particularly to those which are designed for use in connection 15 with ironing boards, for holding the articles as they are pressed, so as to support them in orderly fashion and prevent undue wrinkling or creasing.

The principal object of the invention is 20 to provide an extremely simple and inexpensive, yet a highly efficient, reliable, easily attached and detached clothes rack which may be compactly folded when not in use.

With the foregoing in view, the invention 25 resides in the novel subject matter and arrangement hereinafter described and claimed.

Figure 1 is a top plan view of an ironing board equipped with two of the improved 30 racks.

Figure 2 is a side elevation of the board and one of the racks attached thereto.

Figure 3 is a vertical transverse section on line 3—3 of Fig. 1.

Figure 4 is an enlarged transverse sectional view of one of the racks taken in a different plane from Fig. 3.

Figure 5 is a plan view of one of the racks detached from the ironing board.

Figure 6 is a duplicate of Fig. 5 with the exception that it shows the rack in folded position.

Figure 7 is an edge view of the rack in the condition shown in Fig. 6.

In the drawings above briefly described, I have shown my invention in connection with a common form of ironing board I, and I have illustrated a front rack F and a rear rack R, but as they are both of approximately the same construction, I have confined the major part of the following description to the front rack F.

The numeral 1 designates a horizontal board or other platform which is supported 55 at its ends by a pair of U-shaped members 2 which have their arm connecting or shaft

portions rotatably mounted in suitable bearings 3 carried by the board. The outer arm 4 of each member 2 is comparatively short, while the inner arm 5 is much longer, being 60 bent laterally inward near its upper end as shown at 6, being then extended vertically upward at 7 and finally extending downward and outward, so as to form a hook 8, with its bill 9 extending over the part 6. Due 65 to the taper of the ironing board I, the portion 6 of one rock shaft is shorter than the corresponding portion of the other shaft as will be clear by reference to Fig. 1, but otherwise the two shafts are constructed in 70 the same manner. The corresponding portions 2^a of the rear rack R are of the same general outline as the portions 2, but since it is not necessary to have the rear rack extend to any extent under the ironing board, 75 the hooks 8^a of said shaft portions may be positioned substantially over the inner edge of the rack, whereas the hooks 8 are positioned more nearly over the center of the front rack F, so as to bring the inner portion 8 of the rack under the ironing board and out of the way of the user. The hooks 8 and 8^a are adapted for passage through eyes 10 carried by the edges of the ironing board as shown clearly in Figs. 1, 2 and 3, and the 85 horizontal bills 9 and 9^a of said hooks then underlie the board as illustrated more clearly in Fig. 3, thereby holding the racks against tilting around the hooks and eyes as pivots.

The arms 4 of the rock shaft portions 2 90 and the corresponding arms of the rear rack R, together with the inner arms of said shaft portions are preferably connected by longitudinal links 11 and these links are by preference pivoted to the upper ends of a 95 plurality of comparatively small U-shaped members 12 which may be conveniently referred to as stirrups. These stirrups are held in place by bearings 13 secured to the under side of the platform 1 as shown. 100

When one or both of the racks are applied to the ironing board, they serve as effective means to support the articles as they are ironed and it will be seen that whenever desired, each rack may be detached by simply 105 tilting it in such a manner as to withdraw the hooks from the eyes 10. When detached, the rock shafts and stirrups may be swung downwardly as shown in Figs. 6 and 7 and the platform 1 is by preference formed with 110 a suitable notch 14 to receive the arm portion 6 which swings inwardly when the fold-

ing operation is performed. This notch will of course vary according to the extent of bend of the rock shaft arm and the angle which the portion 6 assumes to the portion 5.

5 Since excellent results may be obtained from the details disclosed, they are preferably followed, but within the scope of the invention as claimed, numerous minor changes may be made. Furthermore, while 10 I have shown two of the racks used upon an ironing board, it will be understood one only may be employed if desired.

I claim:

15 1. A rack comprising a platform, a pair of rock shafts extending transversely of and supporting the ends of said platform, the ends of said rock shafts being provided with upwardly extending arms, longitudinal links pivoted to and extending between the arms 20 of the two rock shafts, and U-shaped stirrups pivoted at their ends to said links, the connecting portions of said stirrups extending beneath said platform, the arms at one end of said rock shafts being provided with 25 means for attachment to relatively fixed supports.

2. A rack comprising a platform, a series of U-shaped members having their arm con-

necting portions rotatably mounted beneath said platform and having their arms extending upwardly above the platform, means for causing said members to rotate in unison, and means for attaching certain of said members to a relatively fixed support. 30

3. A rack comprising a platform, a series 35 of U-shaped members having their arm connecting portions rotatably mounted beneath said platform and having the arms thereof extending upwardly from the platform, links attached to said members to swing them in unison, and means for attaching certain of said members to a relatively fixed support. 40

4. A rack comprising a platform, a plurality of U-shaped members rotatably 45 mounted beneath said platform and having their arms extending upwardly therefrom, lateral extensions upon certain of said arms, said extensions overlying the platform and provided with means for attaching the same 50 to a relatively fixed support, and means for causing said U-shaped members to swing in unison.

In testimony whereof I have hereunto set my hand.

JOHN N. FARIS.
